FIRE DETECTOR

Duane D. Pearsall, Morrison, Colo., assignor to
Statitrol Corporation, Lakewood, Colo.

Filed July 19, 1971, Ser. No. 164,213

Term of patent 14 years

Int. Cl. D29—02

U.S. Cl. D72—1 R

FIG. 1.

FIG. 2.

FIG. 3.

FIG. 4.

FIG. 1 is a front elevational view of the fire detector showing my new design;

FIG. 2 is a right side view thereof in elevation with the left side view being a mirror image thereof;

FIG. 3 is a top plan view thereof; and

FIG. 4 is a bottom plan view thereof.

I claim:

The ornamental design for a fire detector, as shown and described.
